UNITED STATES PATENT OFFICE.

HENRY W. O'DOWD, OF JERSEY CITY, NEW JERSEY, ASSIGNOR, BY MESNE ASSIGNMENTS, TO STANDARD GAS EQUIPMENT CORPORATION, OF BALTIMORE, MARYLAND, A CORPORATION OF MARYLAND.

IGNITION DEVICE FOR GAS RANGES, ETC.

Application filed September 28, 1921, Serial No. 503,972. Renewed November 1, 1924.

To all whom it may concern:

Be it known that I, HENRY W. O'Dowd, a citizen of the United States, residing at Jersey City, county of Hudson, and State of New Jersey, have invented certain new and useful Improvements in Ignition Devices for Gas Ranges, Etc., of which the following is a specification.

The invention relates to ignition devices for gas-ranges, and is particularly designed for lighting burners that are situated under the bottom plates of bake ovens, or housed in closed heat-generating chambers, where they cannot be conveniently reached, in normal operative conditions.

The primary object of the invention is to provide an improved and dependable appliance of the type mentioned whereby the flame from a lighted match, or the like, applied to a tiny jet of gas at or near the front of a range will be immediately transmitted to any part therein where a burner is to be ignited.

Another object is the provision of means insuring the most direct propagation of the flame along a transmitter of the nature set forth, and in such a manner that it will spread smoothly, regularly, and with infallible accuracy from the point of application of the lighting agent to the place of ignition.

A further object is the production of an igniting device of the character described, capable of being positioned so as to operate both above and below the plane of the flame ports of the burner to be lighted, in order that it may check forthwith the flow of unburnt gas first ascending from the latter and prevent accumulation thereof within the range, thus avoiding internal explosions, the spread of noxious fumes, and waste of fuel.

Still another object is to produce a pilot-burner of the species referred to, which shall be of simple construction; easily applied, removed and replaced; convenient to operate; and inexpensive to manufacture.

Other objects and advantages of the invention will in part be obvious and in part be more fully brought out in the following description.

The invention consists of the novel improvements, parts, combinations, and fea-

tures of construction herein shown and described.

Referring to the drawing hereto annexed, for a detailed description of the invention,—

Fig. 1 is a sectional side elevation, showing part of a gas-range within which is mounted a burner furnished with an improved pilot-burner of the kind herein specified;

Fig. 2 is a top plan view of the burner and its pilot-burner, both connected to a fragmentary portion of the front wall of the gas-range; and

Fig. 3 is a longitudinal sectional elevation of the burner alone, shown on a considerably reduced scale.

Fig. 4 is a side elevation of a modification of the invention.

Fig. 5 is a top plan view of the same.

The improved pilot-burner represented in the said drawing is applicable to cooking ranges, or heating apparatus, of any known type or make that can be operated with fuel-gas, or other fluid fuel possessing equivalent calorific properties. It is indifferent also whether the fuel be consumed in one section or another of a gas-range, assuming that the pilot-burner is rightly fitted to the burner therein. For these reasons, only the section containing the heating burner and pilot-burner need be referred to herein, and consequently in the accompanying drawing the illustration has been restricted to showing them merely in connection with the lower portion of a range, the same including simply a heating chamber, as 11, underlying an oven 12, and separated therefrom by a removable plate 13, which constitutes the oven's bottom.

In conformity with the nature of the present invention, heat is generated in the chamber 11 aforesaid by means of a gas-burner 16, which may be of any suitable configuration and manufacture. As shown, this burner is of conventional elliptic form, and mounted lengthwise in the width of the chamber, so that it will reach approximately from end to end thereof at the desired distance below the oven 12. It is provided with the customary terminal supports, as 17, 18, adapted to engage brackets (not shown) in the opposite sides of the range. The several sections of the burner com-

prised in the ellipse further have double rows of perforations or ports 19, 20, serving as gas-jets and constituting as many flame ports when ignition takes place. The 5 perforations, preferably, are arranged in two series, forming elongated annuli, concentrically disposed one within the other.

Gas is supplied to the burner 16 through a mixing chamber in the form of a feed-tube 10 21, that may be cast integral therewith and terminates in an enlarged head 22, constituting an air chamber into which air is drawn with the gas prior to its being consumed.

A supply-pipe 23, controlled by a plug-15 valve 24, discharges the gas into the air chamber which is fitted, in a well-known manner, within an opening provided therefor, as at 25, in the front wall of the range. As will be observed, the tube 21 and head 20 22 thereof extend both at right angles to the said front wall and to the major axis of the ellipse circumscribing the body of the burner.

The pilot-burner or flame transmitter 25 proper, in the embodiment of the invention herein exemplified, consists of a small tube 28, designed for attachment, preferably, to the front wall of the range within the heating chamber 11, and to the burner 16, therein 30 enclosed. As seen in Fig. 1, the tube 28 is placed at an incline with relation to both the chamber and the burner, being made to reach from the upper front corner of the former down to and across the underside of 35 the latter near its forward edge. It is supported by, and put into communication with, the body of the burner through the medium of an offset socket 29, engaging a nipple 30. The socket, as shown in Figs. 1 and 2, is 40 formed on the upper side of the tube 28, intermediately of its length, whereas the nipple, which appears uncovered in Fig. 3, projects obliquely and upwardly from the burner. The nipple and the socket, of 45 course, are oppositely directed in a plane parallel to that of the inclined tube 28, and therefore become readily engaged as the tube is introduced into the heating chamber and set in the position above pointed out.

50 The tube 28 finds another support on the front wall of the heating chamber 11, against which it is adapted to rest. For this purpose, the upper end of the tube is provided with a flat head 32, which extends downward at an angle to its body and constitutes 55 an abutment, bearing squarely upon the inner face of the said front wall. In order to prevent its displacement, the head 32 is flanged on both sides and caused to engage 60 a keeper 33 on this wall, as seen most clearly in Fig. 2.

In addition to being sustained and steadied, both interiorly and exteriorly, by its socket 29 engaging the nipple 30, and its flanged 65 head 32 caught in the keeper 33, the tube 28

is further held in place by the lower end thereof taking under the forward member of the elliptic burner 16, in the manner represented in Fig. 1. A firm setting of the tube is thereby secured, without resorting to 70 the use of screws, rivets, bolts and nuts, or similar fastenings.

Small perforations, as 36, are provided throughout the length of the tube 28, to afford outlets for the gas that enters it from 75 the burner 16, communicating therewith by way of the nipple 30 and socket 29.

By preference and as shown, these perforations are arranged in one side of the tube 80 and are disposed in close relations to each other so as to form a straight and continuous line of jets of diminutive size, which line extending from a point above the burner extends obliquely and rearwardly downward below and beyond the ports of the burner 16, the line of jets of the pilot-burner thus intersecting the plane of the jets of the burner 16. As a result of the construction described, when the jets of the pilot-burner 90 are ignited at the upper forward portion of the tube 28, a flame will be propagated from the upper part of the heating chamber at the front down into the lower middle portion of the same and beneath the burner therein, thereby igniting the jets of the burner 16. 95

For the purpose of lighting the pilot-burner jets an ignition-aperture 38 is formed in the forward edge of the bottom plate 13 of the oven 12, through which the flame from a burning match may be applied. The flame, it is understood, fires the gas emitted by the line of perforations 36, at the right of the tube 28, and is instantaneously transmitted thereby to the outer and inner series of ports, 100 20 and 19, of the burner, which the lower terminal of the tube crosses at substantially right angles in an oblique direction. Thence the line of flame conveyed along the side of the tube spreads out therefrom in like manner around the ellipse of the burner and sets 105 ablaze the gas issuing from its ports. It will be perceived that, owing to the peculiar position given to the tube 28, the lighted jets thereof are well adapted to fire at once all 110 of the gas which may arise in any part of the chamber 12, that is, as soon as it is turned on by opening the plug-valve 24. No unconsumed gas will accumulate in the heating chamber, if only the flame is seasonably applied through the aperture 38, in the bottom 115 of the oven. Due to the location of the aperture 38 in the bottom plate of the oven, it will be necessary in order to gain access to said aperture for the purpose of igniting the pilot-burner jets, to first open the oven door 120 37 thereby reducing the liability of explosion of gas within the oven from a leaky valve.

It will be noted, further, that in the accompanying illustration of the invention, 125 130

chosen as an example, the socket 29 and the nipple 30 are located at the upper part of the burner 16, remote from the flame ports in the latter, which are directed downwardly to face the bottom of the chamber 12, in order to avoid overheating the oven plate 13 thereabove. This is the preferred arrangement. However, it should be understood that the improved flame transmitter forming the subject-matter hereof is applicable as well to burners having ports differently disposed, with obvious transpositions of the means of attachment and gas conveying media that are required to constitute an operative combination.

In Fig. 4 the pilot-burner is shown applied to the heating burner in a different relation from that in the other figures, although the construction of the pilot-burner 20 is the same and its functional operation similar to that first described. In this figure the feed tube 21^a and enlarged head 22^a constituting respectively the mixing chamber and air chamber of the burner, extends from one end of the same axially thereof, and the tube 28^a of the pilot-burner is applied to the forward portion of the burner and extends in substantial parallelism with the mixing chamber, the pilot-burner perforations 36^a extending as in the first instance described, in a line along the side of the tube 28^a and intersecting at its lower end the plane of the ports of the burner 16^a.

In its broader aspect, therefore, the invention is not limited to the precise features of construction and arrangement of parts herein shown and described, nor to any particular construction by means of which it can be carried into effect, as many changes may be made in the details without departing from the principles of the invention and without sacrificing its chief advantages.

I claim:

1. In a gas-range, the combination with a heating chamber, of a heating burner in said chamber having ports disposed at a predetermined plane, a pilot-burner provided with a continuous line of perforations intersecting said plane and disposed on both sides thereof, and means for supplying gas from the heating burner to the pilot-burner; whereby a flame applied to the perforations of the pilot-burner will be transmitted to the ports of the heating burner.

2. In a gas-range, the combination with a heating chamber and an oven superposed thereon, of a heating burner in said chamber having a series of flame ports disposed in a plane approximately parallel to the bottom of the oven, and a pilot-burner provided with a continuous line of jets, said pilot-burner extending across and below the plane of the flame ports and arranged to

propagate a flame from one part of the chamber transversely of, across and below the plane of the flame ports of the heating burner.

3. In a gas-range, the combination with a heating chamber, of a burner mounted therein and provided with an upwardly extending hollow nipple communicating with the interior of the burner, and a pilot-burner extending down to and below the heating burner and provided between its ends with a socket surrounding the nipple and communicating with the interior of the pilot-burner.

4. In a gas-range, the combination with a heating chamber, of a heating burner mounted therein, a pilot-burner formed with a head arranged to bear against a wall of said chamber in a higher plane than that of said heating burner, the body of said pilot-burner being inclined from its head toward the heating burner and being provided between its ends with a longitudinally extending socket offset from the body, and supporting means on the heating burner 90 entering said offset socket to sustain the lower end of the pilot-burner in its proper relation to the heating burner.

5. In a gas-range, the combination with a heating chamber, of a heating burner in said chamber, an obliquely disposed pilot-burner communicating with said heating burner, an anchorage on a wall of the chamber adapted to receive the upper end of said pilot-burner, and means on the latter 100 serving to hold its lower end suspended from and wholly below the heating burner.

6. In a gas-range, the combination with a heating chamber, of a heating burner therein, a pilot-burner inclined down from a wall of said chamber to said heating burner, a tubular element on the latter similarly inclined towards said wall, and a projecting hollow member on said pilot-burner adapted to fit over said tubular element.

7. In a gas-range, the combination with a heating chamber, of a heating burner therein, a pilot-burner extending from a wall of said chamber toward ports of said heating burner, means for anchoring one end of said pilot-burner to said wall, and an interlocking connection between the heating burner and the pilot-burner to hold the other end of the latter adjacent to said ports, said connection being formed of hollow parts affording a communication between the pilot-burner and heating burner and serving to supply gas from the heating burner to the pilot-burner.

8. In a gas-range, the combination with a heating chamber and an oven thereover having an ignition aperture in its bottom, of a heating burner in the heating chamber provided with a series of burner ports, and

a flame transmitter extending down from said aperture transversely of and below said burner ports, said flame transmitter being perforated so as to produce a continuous line of jets extending transversely past and below the burner ports.

9. In a gas-range, the combination with a heating chamber, of an elliptic heating burner in said chamber having ports disposed in concentric annuli therearound, and a flame transmitter provided with a continuous line of jets extending from a wall of the chamber to said heating burner and transversely past and below the ports therein.

10. In a gas-range, the combination with a heating chamber and an oven superposed thereon and provided with an aperture in its bottom, of a heating burner in said chamber having endless series of ports arranged concentrically one series within another, and a flame transmitter provided with perforations constituting a continuous line of jets disposed respectively above and below said series of ports and capable of conveying a flame transversely of said series of ports from said aperture.

11. In a gas range, the combination with a heating chamber and an oven superposed thereon, of a heating burner in said chamber having a series of flame ports disposed in a plane approximately parallel to the bottom of the oven, and a pilot-burner provided with a continuous line of jets arranged to propagate a flame from one part of the chamber transversely of and across the plane of the flame ports of the heating burner.

12. In a gas range, the combination with a heating chamber, of a burner mounted therein and provided with an upwardly extending hollow nipple communicating with the interior of the burner, and a pilot-burner extending down to the heating burner and provided with a socket surrounding the nipple and communicating with the interior of the pilot-burner.

13. In a gas range, the combination with a heating chamber, of a heating burner mounted therein and provided with a nipple communicating with the interior of the burner, and a pilot-burner tube extending to the heating burner and provided in its side with

a hollow socket surrounding the nipple and communicating with the interior of the tube, the said tube being provided with a line of jet openings to propagate a lighting flame.

14. In a gas range, the combination with a heating chamber having an apertured cover, of a heating burner mounted under the latter, a flame transmitting tube provided with perforations leading from the aperture in said cover to the ports of said heating burner, a tubular element in communication with the heating burner at a point remote from its said ports, and a hollow member pertaining to said tube and positioned to engage said element.

15. In a gas range, the combination with a heating chamber, of a heating burner mounted therein, a pilot-burner formed with a head arranged to bear against a wall of said chamber in a higher plane than that of said heating burner, the body of said pilot-burner being inclined from its head toward the heating burner and being provided with an offset longitudinally extending socket, and supporting means on the heating burner entering said offset socket to sustain the lower end of the pilot-burner in its proper relation to the heating burner.

16. In a gas range, the combination with a heating chamber, of a heating burner therein, a pilot-burner arranged to bear against a wall of said chamber at one end and extending to said heating burner at its other end, a hollow suspending member on said pilot-burner communicating with the interior of the same, and a hollow supporting element on the heating burner communicating with the interior of the latter and engaging the said member to supply gas to the pilot-burner.

17. In a gas heater, the combination of a heating burner having flame ports disposed in a predetermined plane, and a pilot-burner extending transversely of said plane on both sides of the same and constructed in its side to propagate an ignition flame lengthwise of the pilot-burner and disposed on opposite sides of the plane of the flame ports of the heating burner.

In testimony whereof, I have affixed my signature hereto.

HENRY W. O'DOWD.
